(57) **CLAIM**

The ornamental design for the speaker system, as shown and described.

DESCRIPTION

FIG. 1 is a perspective view of our speaker system showing our design;

FIG. 2 is a perspective view of a subwoofer for the speaker system;

FIG. 3 is a front plan view thereof;

FIG. 4 is back plan view thereof;

FIG. 5 is a top plan view thereof;

FIG. 6 is a bottom plan view thereof;

FIG. 7 is a left side plan view thereof; and

FIG. 8 is a right side plan view thereof.

FIG. 9 is a perspective view of a speaker for the speaker system;

FIG. 10 is a front plan view thereof;

FIG. 11 is back plan view thereof;

FIG. 12 is a top plan view thereof;

FIG. 13 is a bottom plan view thereof;

FIG. 14 is a left side plan view thereof;

FIG. 15 is a right side plan view thereof; and

FIG. 16 is right side plan view thereof shown as it would look on a surface.

FIG. 17 is the perspective view of a volume control for the speaker system;

FIG. 18 is the front plan view thereof;

FIG. 19 is a back plan view thereof;

FIG. 20 is a top plan view thereof;

FIG. 21 is a bottom plan view thereof;

FIG. 22 is a left plan view thereof;

FIG. 23 is a right plan view thereof;

FIG. 24 is the left plan view thereof with a slider switch in a second position;

FIG. 25 is the left plan view thereof with the slider switch in a third position; and,

FIG. 26 is the left plan view thereof shown as it would look on a surface.
